UNITED STATES PATENT OFFICE

2,068,076

APPARATUS FOR MAKING WING-NUTS

Heyman Rosenberg, New York, N. Y.

Application August 12, 1932, Serial No. 628,569

10 Claims.

(Cl. 10—72)

This invention relates to improvements in apparatus for making wing-nuts, and has as its essential object complete automatic handling and treatment of wing-nut blanks for producing wing-nuts.

A further object is improvement in the treatment of wing-nut blanks over the manner of treating the same according to the teachings of my co-pending application Serial No. 612,327, filed May 19, 1932.

An object of the invention is to deliver blanks successively one at a time to a carrier or transfer device and to effectively retain all other blanks against access to such carrier during delivery by the carrier of a blank to the dies.

A further object is to safeguard against the misfortune of a misplacing of a blank in its engagement with the carrier, and to provide for extraordinary release of a blank when required incident to such a misplacement.

Another object of the present invention is the production of a nut body of especially exact, accurate, and well formed contour free from those slight defects that frequently arise incident to the presence of an ejector plunger functioning through the male die; and a further object is the provision of means for effectively stripping nuts from such die without the necessity for a plunger within the die.

A still further object is the formation of a depression in the base of the nut in the course of the shaping of the nut, which depression is located and proportioned to provide a countersink or bevelled end portion to the bore of the nut which thus prevents the outstanding of a bur at the base of the nut incident to the action of a tap forming threads in the nut.

With these and further objects in view as will in part hereinafter become apparent and in part be stated, the invention comprises certain novel constructions, combinations, and arrangements of parts as subsequently specified and claimed.

In the accompanying drawings,—

Figure 1 is a view partly in side elevation and partly in section of an apparatus embodying the features of the present invention, the parts being shown in the position where a new blank has just been inserted in the female die by the feeder plunger, an additional blank has just been released in the feeder tube to the carrier, and a nut is about to be stripped from the male die.

Figure 2 is a similar view of the same with the parts in the position of the second step in the cycle of operation where the feeding of blanks through the feeder tube is prevented and the male

die has just completed its nut-forming stroke within the female die.

Figure 3 is a transverse, vertical section taken on the plane indicated by line 3—3 of Figure 1, and looking toward the female die.

5

Figure 4 is a top plan view of the apparatus seen in Figures 1 and 2, parts being broken away for disclosing parts beneath.

Figure 5 is an enlarged, vertical section through the supply hopper and upper end portion of the feeder tube, parts being seen in elevation showing the action of feeding a blank to the feeder tube.

Figure 6 is a sectional elevation of the lower portion of the feeder tube showing the action of the spring-pressed detent for locking out the blanks and preventing feeding thereof along the tube during certain movements of the balance of the apparatus.

Figure 7 is a view similar to Figure 5 taken from a plane at right angles to the plane of the section of Figure 5.

Figure 8 is an enlarged, fragmentary, longitudinal section through the lower end portion of the feeder tube showing the spring-stressed release gate.

25

Figure 9 is a vertical section through a wing-nut so far as completed by the present apparatus, and indicating in dotted lines the position of the bore to be formed through the body of the nut.

As stated in my said co-pending patent application, standard headers for rivet making operate faster than stamping mechanism, and where headers may be used in lieu of stamping machines other savings are effected, and it is an object of the present invention to achieve all of the objects above pointed out while utilizing a standard header for the production of nuts and particularly wing-nuts.

Referring to the drawings by numerals, 1 indicates the usual framework of a standard header through which extends a transversely-arranged reciprocating bar 2, the bar 2 being part of the standard header mechanism and connected to the source of power in the usual and well known manner. Fixed to and carried by the bar 2 at 45 the inner end portion thereof is the carrier 3, which corresponds to the like carrier shown in detail in my above-mentioned co-pending application. Since the carrier 3 is shown, described, and claimed in detail in my said co-pending application, brief reference thereto is all that will be required. The carrier 3 is made up of a main plate connected by a bolt 4 with the bar 2. A stop 5 is fixed to the frame 1 in position to interrupt return movement of a bar 6 slidingly 55

carried by the under edge of the main plate of the carrier 3. The bar 6, as seen in detail in my said co-pending application, is slotted longitudinally and held by bolts 7, 7, against detachment 5 from said main plate while being left free to slide, and the bar 6 is preferably stressed by a spring, not illustrated, in a direction toward the stop 5. A clamping jaw 8 is pivoted to the forward end of the bar 6, and is stressed by a spring 9 rearward or toward a clamping position. The inner or operative clamping face of the jaw 8 is preferably grooved, as seen in my said co-pending application, to adapt it to snugly engage a nut blank, and the main body of the carrier 3 is 10 correspondingly oppositely notched in its end portion so that the wing part of a wing-nut blank can be clamped between the jaw 8 and the said main plate. Portions of the said main plate are cut away or notched to accommodate the 15 passage of a feeding plunger, when the blank is to be moved from the carrier 3 into engagement with the female die, as hereinafter described. A finger 10 is pivotally carried by the main plate of the carrier 3 and stressed by a spring 11 to 20 position for serving as a guide for a nut blank while capable of moving pivotally laterally when required to allow movement of the blank.

Arranged with its bore in line with the space 25 between the jaw 8 and the main plate of carrier 3, when the carrier is in its rearmost position, is a nut blank feeding tube 12 located to deposit blanks in position to drop past the finger 10 into the space between the jaw 8 and the main plate of carrier 3, so that, when the carrier begins its 30 inward movement and the stop 5 allows the spring to pull the slide plate 6 to the jaw-clamping position, the blank will be clamped between jaw 8 and the adjacent edge of the main plate of the carrier and thus firmly held until brought 35 to a position in line with the female die.

At the upper end of the tube 12 is preferably arranged a hopper or supply box 13 having a discharge opening 14 in its base and a downwardly-extending sleeve 15 surrounding said discharge opening and proportioned to snugly receive the upper end portion of the tube 12. The upper end of the tube 12 is preferably reamed out or otherwise counterbored or treated to provide a flared portion 16 to aid in guiding blanks 40 to an upright position. A bracket or other appropriate support 17 is preferably fixed to the bar 2, or other means of reciprocation, and bracket 17 carries a flexible brush 18 which may be of leather, fabric, or other appropriate material, and is preferably detachably carried directly by a plate 19 having an arm or shank 20 upstanding and adjustably engaged in an eye 21 forming part of a rod 22 adjustably fixed to the bracket 17. The parts 20, 22, and 17 are preferably adjustably connected by set screws 23, though other connections may, of course, be provided. Of course, any of numerous other arrangements may be made for providing a brush within the hopper 13 connected to a reciprocating part of the header mechanism, so as to cause the brush 18 to reciprocate within the hopper in the space above and across the discharge opening 14, whereby a batch or mass of nut blanks within the hopper is agitated and those blanks 45 lying improperly with respect to the discharge opening 14 to fall into the same will be moved out of the way and allow others to fall after the manner indicated in Figure 5.

It is to be noted that the discharge opening 14 50 is of greater diameter than one-half the length

of a nut blank and of less diameter than the full length of the blank, so that, under no circumstances, can a blank fall into the opening 14 edgewise, and when a preponderating bulk of the blank overhangs the opening 14 the blank 5 will fall by gravity into the opening and will have a turning movement, as indicated in dotted lines in Figure 5, until the blank is thus brought to an upright position, so that the blanks descend in the tube 12 after the manner shown in Figure 10 6. There is no possibility of clogging and the tube 12 is of ample diameter to allow free feeding of the blanks arranged end to end.

The present invention relates more particularly to the formation of wing-nuts and in the 15 constructing of the wing-nuts the blanks are prepared by severing sections of wire of the required length and then compressing the wire lengthwise in an appropriate die to cause the body of the thus severed section to swell approximately midway of its length into a bulbous enlargement which is to become the body of the finished nut while the parts of the wire section beyond the bulbous enlargement at either side are to form the wings. Thus, the nut blanks for 20 forming wing-nuts each consists of a central enlargement 24 and lateral extensions or wing portions 25, 25, and are prepared to this condition before being supplied to the hopper 13.

In my said co-pending application apparatus 30 is illustrated and described whereby nut blanks are allowed to rest on the upper edge of the reciprocating carrier during its full stroke, so that the carrier itself is depended upon to segregate each blank received from the succeeding blanks 35 which remain up in the feeder tube, but the present invention contemplates segregation of the blanks independently of the carrier so as to allow the next succeeding blank to be fed into the carrier to engage the upper edge of the carrier only 40 for a minimum time. To this end, a detent is provided for the nut blanks within the tube 12, and the said detent preferably consists of a pin or finger 26 disposed to reciprocate through an opening 27 in the wall of tube 12 to successively 45 intercept the descent of the blanks within the tube. The detent pin 26 is carried by an operating lever 28 pivoted at 29 either to the tube 12 or to an appropriate bracket 30 which sustains the tube. The bracket 30 is mounted on and 50 preferably fixed to the frame 1, as by a bolt 31. The lever 28 is adapted to be tripped by any appropriate mechanism, such as hereinafter described, and is spring stressed, as by spring 32, so as to be held constantly in the position seen in 55 Figure 6 in engagement with a nut blank within tube 12, except when tripped. A convenient arrangement of the spring 32 disposes it in position to have its outer or free end seated in a recess 33 in the upper end of the lever 28, but any of 60 other convenient arrangements may be provided. A tap-receiving head 34 is preferably formed on the upper end of the lever 28 to receive the tripping taps of a finger 35 carried by a bracket 36. Finger 35 is preferably in the form of an adjustable part carried by the bracket 36, and a bolt with appropriate locking nuts affords a successful operating finger 35, but, of course, the finger may be formed integral with bracket 36, or otherwise constructed to function effectively in its 65 action on lever 28.

The standard header of which the present invention is an improvement is provided with a main plunger head 37, which is well known, as actuated with two reciprocations, one a main body 70

or horizontal reciprocation to effect the rivet heading or die stamping operation, and the other a vertical movement between die stamping operations to bring the required plungers or dies or feeding fingers, as the case may be, into proper alinement. The main plunger head 37 carries the bracket 36, so that at one of its die-stamping strokes the finger 35 contacts with the lever 28 and trips the same so as to release the detent 26 from engagement with the blanks within tube 12, but as the plunger head 37 is moved upward for the next die-stamping stroke, the finger 35 will be out of alinement with lever 28, as plainly seen in Figure 2, and the tripping action will, therefore, not occur. The stroke of the finger 35 against the lever 28 is a relatively quick one, and the finger is removed from contact with the lever quickly enough to allow the detent 27 to move back to its blank-engaging position as soon as the previously engaged blank has moved by gravity past the place of the detent 26 and before the next succeeding blank can pass the detent, so that the detent engages the next succeeding blank and sustains the column of blanks after the manner seen in Figure 6 until the next tripping of the lever 28. Thus, a blank is dropped along tube 12 below detent 26 with each alternating die-stamping stroke of the main plunger 37, and the reciprocation of the bar 2 is timed relative to the strokes of the main plunger 37 such that the new blank is dropped by the detent 26 just as the old blank is being moved from the carrier 3 into engagement with the female die and the newly dropped blank therefore descends to rest endwise on the upper edge of the main plate of the carrier 3 where it remains in sliding engagement while the carrier is brought back to the position seen in Figure 3 where the newly dropped blank again drops and this time into contact with the slide plate 6 where it is gripped by the jaw 8 with the next inward thrust of the carrier 3.

Main plunger head 37 carries the male die 38 which corresponds with the male die shown in my above-identified co-pending application but differs therefrom in that die 38 has no internal or ejecting plunger, and is, therefore, a complete, integral, imperforate mass. Above the die 38 the main plunger head 37 carries a projecting finger 39 positioned for engaging a nut blank when the blank has been located by the carrier 3 in line with the female die, whereby movement of the main plunger head 37 in that forward stroke or die-stamping stroke, when the finger 39 is in line with the female die, is destined to push the blank from the carrier 3 bodily edgewise into engagement with the female die, and this action occurs at the same time that the finger 35 engages and trips the lever 28.

The frame 1 carries the female die 40 in the line of the strokes of the die 38 and finger 39 as they are alternately brought the one to its lower position and the other to its upper position in the successive strokes of the main plunger head 37. Die 40 is provided with upper and lower spring jaws 41 positioned to engage the ends of a nut blank as the nut blank is forced into contact with the die by the action of the finger 39. The die 40 is recessed and provided with upper and lower lateral grooves 42, 42, to receive the wing portions 25 of the blank while the bulbous enlargement 24 engages the contiguous end of an ejector plunger 43 extending axially through the die 40 and exposed within the die recess. The plunger 43 is engaged by an alined push rod 44 which in turn engages thrust mechanism, not shown here-

in, but illustrated in my said co-pending application, timed to retain the plunger 43 in its rearward position or position seen in Figure 2 as the blank is being formed by the male die 38 into the die recess of die 40 and to follow the blank outward to substantially the position seen in Figure 1 to insure ejection of the blank as the die 38 is moving back from the position seen in Figure 2. The plunger 43 is provided with a particlular, centrally located, endwise projection 45 10 at its end extending into the die recess of die 40.

The die 38 is provided with lateral grooves 46, 46, adapted to oppose and cooperate with the grooves 42 in accommodating the wing portions 25, and the apex of the die 38 is provided with 15 a recess 47 (see Figure 4) having the contour of the body of the finished nut.

Pivoted to the frame 1, as at 48, is a nut stripper consisting of a lever bar 49, a finger 50 carried at the free end thereof, and a spring 20 57 stressing the lever bar to a nut-engaging position. The finger 50 has a bevelled or rounded face 52 presented toward the approaching nut as the die 38 moves toward the lever bar 49, so that the stripper is adapted to be cammed by the 25 inclined wall 52 engaging one of the inclined wings of the nut, so that the finger 50 automatically assumes a position in the rear of the nut when the nut is brought forward with the stroke of the 30 plunger head 37 that causes finger 39 to push 30 a nut blank into engagement with die 40. The stripper is shown pivoted in an appropriate recess in the body of the frame 1, but, of course, may be otherwise located as found most convenient.

In operation, the blanks are supplied to the 35 hopper 13 in sufficient quantities to keep the machine supplied with blanks, and aside from defects developing in the various parts of the mechanism owing to wear and the like, the machine requires no attention of an operator, but 40 is thoroughly and completely automatic, so that one operator can easily look after a dozen or more headers constructed in accordance with the present invention and provided with the parts 45 for nut-forming operations. By contrast, stamping machines, though working slower than headers, require each an operator so that the present invention represents a very substantial saving in the cost of operation. The blank reaching the carrier 3 drops between the inner end edge of the 50 main plate of the carrier and the jaw 8, and then the carrier begins to move from the position seen in Figure 3 to a position locating the blank in line with the jaws 41 and upon a very slight movement in that direction the jaw 8 is 55 allowed to clamp the blank so as to hold it against displacement during its travel to the position in front of the die 40. The movement of the carrier away from stop 5 permits the clamping action of the jaw 8. If by any possible 60 mishap the blank fails to reach a proper position on the carrier 3, as seen in Figure 3, so that any part of the blank remains upstanding above the carrier, there is no clogging or obstruction incident to such mishap, because an 65 emergency release gate 53 is provided to close an otherwise laterally open section of the lower end portion of tube 12. The gate 53 is pivoted at 54 to the main portion of the tube, and a spring 55 fixed to the tube at one end at its free end 70 engages the gate 53 and retains the same closed under all normal conditions. The spring 55, however, allows the gate 53 to swing open to permit the passage of an upwardly projecting portion of an incompletely seated blank, so that 75

- clogging or failure of operation will not occur even if a blank should fail to be completely and properly seated in the carrier 3 when the carrier begins its movement to the feeding position.
- 5 Such an improperly seated condition of the blank, however, almost never occurs, and in the few instances where it has been known to occur, the blank has invariably dropped to a fully seated position properly located in the carrier 3 as soon 10 as it has passed the gate 53.

When the carrier 3 reaches the position with the blank in line with the clamping jaws 41, the finger 39 will be approaching the blank within the carrier, and striking the blank will thrust it 15 laterally from the carrier 3 to a gripped position between the spring jaws 41. This movement is quickly accomplished and the finger 39 immediately recedes with the return movement of the main plunger head 37. As the finger 39 presses 20 the blank to the position between spring jaws 41, the finger 35 trips lever 28 and allows a new blank to drop down to the upper edge of the main plate of carrier 3, so that the new blank will be ready to drop to the position seen in Figure 3 as 25 soon as the carrier returns to its blank-receiving position. When the plunger head 37 has made its receding stroke, it moves upward and makes a second advance stroke causing the die 38 to move into the die recess of die 40 and press the blank 30 to the required body formation within the recess 47, and at the same time bend the wing portions 25 to the inclined positions seen in Figure 2, so that they lie in the registering grooves 42 and 46. Meanwhile, the plunger 43 will have been 35 held against movement after receding to the position seen in Figure 2 as the die 38 advances the nut blank in the recess of die 40. By remaining stationary in the position seen in Figure 2, the plunger 43 causes the bulbous projection 45 to 40 form a substantial recess 56 in the nut 57 formed by the action of the dies 38 and 40. Of course, the part referred to as the nut 57 is not a completed nut, but is in the advance state seen in detail in Figure 9 where to complete the nut the 45 body of the nut must be perforated, as indicated in dotted lines at 58, and then tapped to provide the required thread; and it is preferable also to flatten the wing portions of the nut after the operation of the dies 38 and 40. It will be noted 50 that the recess 56 is of sufficient depth and diameter relative to the bore 58 to be formed in the nut that, when the nut is tapped, the bur that is inevitably produced at the lower end portion of the die will appear within the recess 56 and 55 not be exposed beyond the base of the nut, and such base is, therefore, left smooth and flat and enables an easy and perfect manual seating of the nut against the engaged work.

When the parts have reached the position seen 60 in Figure 2, the nut will have thus been given its completed formation so far as the present improved apparatus and process are concerned and now remains only the ejection of the thus formed nut. Should the nut remain within the die recess of die 40 as the die 38 recedes, the plunger 43 will in advancing from the position seen in Figure 2 to the position seen in Figure 1, which it does as the die 38 recedes, eject the blank from the die 40. But the nut seldom remains in the 65 die 40. It usually clings to the die 38, as seen in Figure 1, and in that event moves with the die throughout the receding stroke of the main plunger head 37 and through its downward stroke and then with the forward stroke to the position seen 70 in Figure 1 where the nut is in engagement with 75

the stripper and will be removed by the stripper from die 38 with the beginning of the next receding movement of the die. As the die 38 approaches the position seen in Figure 1, the carrier 3 places a blank in line with the spring jaws 41, 5 and the finger 39 forces the blank between said jaws, as seen in Figure 1, and thus the first cycle of the next new operation is begun as the final cycle of the former operation is being completed.

What is claimed is:—

1. In apparatus of the class described, the combination, with wing-nut stamping means and a reciprocating carrier for bodily carrying wing-nut blanks for delivering blanks to the stamping means, the carrier having a main plate and a resiliently movable jaw spaced with respect to the plate sufficiently for accommodating an arm of the blank between the jaw and plate, the carrier having a support for the blank located to be engaged by the lower end of said arm when disposed 20 between the jaw and plate for sustaining the blank in an upright position with the bulbous enlargement out of the line of the jaw, whereby a wing-nut blank of the type stated is adapted to be received, carried, and released by said carrier 25 with the blank in an upright position, of a tube for delivering blanks to the carrier, the tube being located with its discharge end contiguous to the carrier for discharging wing-nut blanks to the carrier in an upright position and the tube having 30 a lateral opening at its lower end portion for the lateral passage of a portion of a wing-nut blank extending from the carrier during a feeding stroke thereof for enabling the blank to move laterally out of the tube while in an upright position and while the upper portion of the blank is not below the lower end of the tube.

2. The combination as claimed in claim 1 with means for closing the said lateral opening of the tube.

3. The combination as claimed in claim 1 with a pivotally mounted gate for closing the lateral opening of the tube, and means elastically stressing the gate toward its closed position.

4. In die-stamping apparatus for nuts, the combination of cooperating dies for shaping wing-nut blanks, and means for moving one of the dies with respect to the other for causing the dies to shape a wing-nut blank therebetween, one of said dies being imperforate and the other die 50 being perforate, the imperforate die being adapted to have portions of a nut blank formed about its exterior portion, and means for stripping nut blanks axially from the imperforate die by a longitudinal pull.

5. The combination as claimed in claim 4 the stripping means comprising a resiliently stressed detent disposed in the path of the blank on the imperforate die to move under its resilient capacity with movement of the blank in one direction and to resist movement with movement of the blank in the other direction.

6. The combination as claimed in claim 4 wherein the stripping means comprises a resiliently stressed detent external of the imperforate die 65 for stripping wing-nut blanks therefrom.

7. The combination as claimed in claim 4 wherein one of the dies is internally recessed and the other is shaped to enter said recess for the nut-forming operation, and the latter die is the 70 imperforate die.

8. In apparatus for cold forging wing-nut blanks the combination of a matrix or internal die and a cooperating plunger die adapted to bend a blank in the matrix die, the plunger die 75

- being exteriorly shaped to conform generally with the contour of unfinished wings and other parts of a wing-nut blank whereby the bending operation of the plunger die causes the blank in the 5
matrix die to be shaped about and enclose external parts of the plunger die, and a stripper for removing a wing-nut blank from the plunger die.
9. A plural stroke header for making wing nuts comprising, in combination, cooperating dies for 10
shaping wing nut blanks and for moving one of the dies with respect to the other to cause the dies to shape a wing nut blank between them at the forming stroke, the movable die being imperforate, and the stationary die being perforate,
- 15
stripper means associated with the perforate die, the imperforate die being provided with a tapered end having longitudinal grooves at opposite sides thereof so that a wing nut blank may be forged about the exterior of the imperforate die and 20
will be carried away by the imperforate die from the position in which it is so forged, and a strip-

per finger adapted to pass behind the blank on the movable imperforate die as the die advances at the non-forming stroke and to strip the blank from the die as the die retreats.

10. A plural stroke header for making wing nuts comprising, in combination, cooperating movable and stationary dies, means for moving the movable dies to cause the dies to shape a wing nut blank between them at the forming stroke, the movable die being imperforate and 15
adapted to have the wing nut blank formed about its exterior, said dies being so constructed and arranged that the blank is carried away from the forming position by the movable imperforate die, and a stripper adapted to cam over and engage 20
behind the blank as the blank is carried forward at the non-forming stroke of the movable die, and to strip the blank longitudinally from the movable die as the movable die retreats.

20

HEYMAN ROSENBERG.
